CLAIM

The ornamental design for a bottle, as shown and described.

DESCRIPTION

FIG. 1 is a front, top perspective view of a bottle, showing our new design;

FIG. 2 is a rear, top perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is a front perspective view of the bottle in an example use condition.

The broken lines show portions of the bottle that form no part of the claimed design. Further broken lines in FIG. 9 are for the purpose of illustrating the environment and form no part of the claimed design.

1 Claim, 9 Drawing Sheets
